ATTORNEYS

UNITED STATES PATENT OFFICE.

MAX MAYER, OF NEW YORK, N. Y.

DESIGN FOR A DISPLAY-RACK.

SPECIFICATION forming part of Design No. 23,655, dated September 25, 1894.

Application filed April 26, 1894. Serial No. 509,159. Term of patent 3½ years.

To all whom it may concern:

Be it known that I, MAX MAYER, a citizen of the United States, and a resident of the city, county, and State of New York, have invented and produced a new and original Design for Display-Racks, of which the following is a specification.

My design for display racks consists essentially in the configuration shown in the accompanying drawing which is a perspective view of a display rack made after my design.

In the drawing, A represents a curvilinear support of the rack having bends or coils B at its ends and loops D along its length.

E is a second support for the rack having sinuosities e along its length.

F is a brace forming a chord to the arcs described by the supports A and E.

G are brace-like pieces extending from the support A to the brace F and crossing the support E.

H is a crutch-like back support.

What I claim is—

The design for a display rack, substantially as herein shown and described.

MAX MAYER.
